UNITED STATES PATENT OFFICE.

CHARLES G. ERICSON, OF TORONTO, ONTARIO, CANADA.

RAIL ANCHOR.

Application filed October 6, 1924. Serial No. 741,937.

To all whom it may concern:

Be it known that I, CHARLES G. ERICSON, resident of the city of Toronto, in the county of York, Province of Ontario, Canada, a subject of the King of Great Britain, have invented certain new and useful Improvements in Rail Anchors, of which the following is a specification.

This invention relates to rail anchors of the type employing a yoke embracing the rail base flange and a wedge shaped shoe driven between one edge of the flange and provided with an abutment adapted to engage the side of a tie.

15 In my co-pending application No. 741,936, dated Oct. 6th, 1924, I have disclosed a rail anchor provided with a form of shoe which by cutting, bending and forging can be cheaply made from flat metal plates or bars.

20 In the present invention my object is to devise an anchor in which the weight of metal in the shoe is considerably reduced without material reduction in the strength or security of grip on the rail.

25 I attain my object by means of the constructions hereinafter described and illustrated in the accompanying drawings in which—

Fig. 1 is a plan view of a blank from which the wedge shoes are formed;

Fig. 2 a plan view of a complete rail anchor constructed in accordance with my invention in position on a rail;

Fig. 3 an end elevation of the same;

Fig. 4 a side elevation of the same;

Fig. 5 an end elevation showing a slight modification;

Fig. 6 a plan view of the same; and

Fig. 7 a side elevation of part of the end of the larger hook of the yoke member of the anchor, showing the angle of its under surface relative to the upper surface of the rail base.

In the drawings like numerals of reference indicate corresponding parts in the different figures.

In Fig. 1 is shown a blank cut from a metal plate of suitable thickness. This blank is bent up as shown in the drawings to form a member 2 adapted to fit against or over the edge of the rail base, and the integral abutment member 3 extending downwardly and adapted to engage the side of the tie.

55 To adapt the wedge shoe for use with the

yoke hereinafter described, a portion of the under side of the shoe is required to lie at an angle with the under side of the rail base, and for a purpose which will hereinafter appear the entering end of the wedge shoe 60 is also bevelled back.

In the form of wedge shoe shown in Figs. 2, 3 and 4, the under side of the shoe is forged or ground to form the bevel surface $a-b$ (see Fig. 4) while on the back of the 65 entering end is formed the bevelled surface $c-d$, which is somewhat shorter than the bevelled surface $a-b$ and has an angle of bevel slightly greater.

With this shoe co-acts the yoke member 4, 70 preferably formed of steel bent at one end to form the hook 5 adapted to engage one edge of the rail base, while the other end is provided with the hook 6 adapted to embrace the wedge member 2 and to engage the 75 upper side of the rail base between the edge and the web.

The under side of the end of the hook 6 is bevelled to provide an engaging surface, and the angle of the bevel is slightly less 80 than the angle of the upper side of the rail base to the under side whereby a full contact against the rail base is ensured by the surface 7 after the yoke has been driven to operating position on the shoe and rail. Before the yoke has been driven to position the parts appear as shown in Fig. 7.

The device is positioned on the rail base in the ordinary manner and the yoke driven over the shoe. The bevelled surface $c-d$ on 90 the wedge shoe facilitates the entry of the wedge shoe into the hook 6 and serves also to tighten the yoke transversely of the rail. It, however, owing to it being shorter than the bevelled surface $a-b$, ceases to operate 95 before the bevelled surface $a-b$ has ceased to function. Hence it does not interfere in any way with the drawing down of the inner end of the hook 6 into tight engagement with the upper surface of the rail base.

100 The surface $c-d$ has been described as having a greater angle of bevel than the surface $a-b$. This facilitates the introduction of the end of the wedge shoe into the hook and at the same time ensures that the bevelled surface will cease to function on the yoke before the bevelled surface $a-b$.

105 The parts of the wedge shoe adjacent the abutment end are of parallel section, so that 110

after the wedge shoe and yoke have been tightened on the rail base by driving the one over the other, the yoke may be driven along the wedge shoe into close engagement with the abutment 3 without imposing stresses on the yoke member liable to break it. The yoke member may thus be used to reinforce the abutment and enable the wedge shoe and abutment to be formed from lighter gauge material than would otherwise be possible.

After the yoke has been finally positioned relative to the wedge shoe, it is readily driven to a diagonal position relative to the rail base as is common practice in the art.

The arching of the hook 6 around the wedge shoe gives the hook an arc of curvature of over 180° and brings the stresses tending to spread the hook to a position 20 some distance inwardly of the bottom of the throat of the hook, so that the wedging action tending to spread the hook is applied where it is least effective in causing stresses tending to break the yoke adjacent the plane 25 of the edge of the rail base.

A modified form of the invention is shown in Figs. 5 and 6 in which the edge of the metal blank from which the shoe is formed is bent over to simply engage against the 30 side of the edge of the rail base and not to hook over it as in the form shown in Figs. 2, 3 and 4. The back and under side of the wedge shoe are thereafter suitably bevelled to form as in the former construction.

35 What I claim is:—

1. A rail anchor comprising a wedge shoe adapted to engage the edge and underside of a rail base; a yoke member adapted to span the rail base and having a hook at one 40 end adapted to engage one edge of the rail base and a hook at the other end adapted to embrace the shoe and to engage the upper side of the rail base between the edge and the web, the said wedge shoe having its underside bevelled adjacent the yoke entering end to exert a downward pressure on the yoke to draw the end of its shoe embracing hook into contact with the upper surface 45 of the rail base.

50 2. A rail anchor comprising a wedge shoe adapted to engage the edge and underside of a rail base; a yoke member adapted to span the rail base and having a hook at one end adapted to engage one edge of the rail base and a hook at the other end adapted to embrace the shoe and to engage the upper 55 side of the rail base between the edge and the web, the said wedge shoe having its underside bevelled adjacent the yoke entering end to exert a downward pressure on the yoke to draw the end of its shoe embracing hook into contact with the upper surface of the rail base, the outer side of said shoe adjacent the yoke entering end also being bevelled, the bevel being shorter than that 60 65 of the under side so that it ceases to function before the first mentioned bevelled surface.

3. A rail anchor comprising a wedge shoe adapted to engage the edge and underside 70 of a rail base; a yoke member adapted to span the rail base and having a hook at one end adapted to engage one edge of the rail base and a hook at the other end adapted to embrace the shoe and to engage the upper 75 side of the rail base between the edge and the web, the said wedge shoe having its underside bevelled adjacent the yoke entering end to exert a downward pressure on the 80 yoke to draw the end of its shoe embracing hook into contact with the upper surface of the rail base, the outer side of said shoe adjacent the yoke entering end also being bevelled, the bevel being shorter than that 85 of the underside and the angle of bevel slightly greater so that it ceases to function before the first mentioned bevelled surface.

4. A rail anchor comprising a wedge shoe adapted to engage the edge and underside of a rail base; a yoke member adapted to span 90 the rail base and having a hook at one end adapted to engage one edge of the rail base and a hook at the other end adapted to embrace the shoe and to engage the upper side of the rail base between the edge and the 95 web, the said wedge shoe having its underside bevelled adjacent the yoke entering end to exert a downward pressure on the yoke to draw the end of its shoe embracing hook into contact with the upper surface of the rail base, the outer side of said shoe adjacent the yoke entering end also being bevelled, the angle of bevel being slightly greater than that of the underside so that it ceases to 100 function before the first mentioned bevelled surface.

5. A rail anchor comprising a wedge shoe adapted to engage the edge and underside of a rail base; a yoke member adapted to span the rail base and having a hook at 110 one end adapted to engage one edge of the rail base and a hook at the other end adapted to embrace the shoe and to engage the upper side of the rail base between the edge and the web, the said wedge shoe having its underside bevelled adjacent the yoke entering end to exert a downward pressure on the yoke to draw the end of its shoe embracing hook into contact with the upper 115 surface of the rail base, the yoke engaging surfaces of the shoe adjacent the abutment end of the anchor being substantially parallel.

6. A rail anchor comprising a wedge shoe adapted to engage the edge and underside of a rail base; a yoke member adapted to span the rail base and having a hook at one end adapted to engage one edge of the rail base and a hook at the other end adapted 125 to embrace the shoe and to engage the up- 130

per side of the rail base between the edge and the web, the said wedge shoe having its underside bevelled adjacent the yoke entering end to exert a downward pressure 5 on the yoke to draw the end of its shoe embracing hook into contact with the upper surface of the rail base, the outer side of said shoe adjacent the yoke entering end also being bevelled, the bevel being shorter 10 than that of the underside and ceasing to function earlier, the yoke engaging surfaces of the shoe adjacent the abutment end of the anchor being substantially parallel.

7. A rail anchor comprising a wedge shoe 15 adapted to engage the edge and underside of a rail base; a yoke member adapted to span the rail base and having a hook at one end adapted to engage one edge of the rail base and a hook at the other end adapted 20 to embrace the shoe and to engage the upper side of the rail base between the edge and the web, the said wedge shoe having its underside bevelled adjacent the yoke entering end to exert a downward pressure on 25 the yoke to draw the end of its shoe embracing hook into contact with the upper surface of the rail base, the outer side of said shoe adjacent the yoke entering end also being bevelled, the bevel being shorter 30 than that of the underside and ceasing to function earlier and the angle of bevel slightly greater, the yoke engaging sur-

faces of the shoe adjacent the abutment end of the anchor being substantially parallel.

8. A wedge shoe for a rail anchor formed 35 of malleable plate metal having one side folded over to form a lip adapted, when the shoe is in engagement with the underside of a rail base to engage the side of the edge of the base. 40

9. A rail anchor comprising a wedge shoe adapted to engage the edge and underside of a rail base; a yoke member adapted to span the rail base and having a hook at one end adapted to engage one edge of the rail 45 base and a hook at the other end adapted to embrace the shoe and to engage the upper side of the rail base between the edge and the web, the said wedge shoe having its underside bevelled adjacent the yoke entering end to exert a downward pressure on 50 the yoke to draw the end of its shoe embracing hook into contact with the upper surface of the rail base, the underside of the said end of the yoke being bevelled at 55 an angle slightly less than the angle of the upper side of the rail base to ensure a full contact against the rail base after the yoke has been driven to operating position on the shoe and rail. 60

Signed at Toronto this 20th day of September, 1924.

CHARLES G. ERICSON.
